VOTING MACHINE

Filed March 23, 1927 3 Sheets-Sheet 3

UNITED STATES PATENT OFFICE

HIRAM B. SWARTZ, OF WOOSTER, OHIO

VOTING MACHINE

Application filed March 23, 1927. Serial No. 177,584.

My invention relates to improvements in voting machines and particularly, of the type shown in Letters Patent issued to me, numbered 635,869, in which slidable voting keys are used.

Voting machines, to meet all legal requirements, must provide not only means for actuating counters unerringly and without the possibility of fraudulent manipulation, but also simple and adequate means for voting in secret either a straight party ticket, or a mixed ticket for candidates of the voter's choice either singly or in groups for the same office, also for either or both partisan and non-partisan candidates or groups thereof as may be required at an election; also means for voting at both general and primary elections, and on propositions or questions submitted; also means for voting either for nominees named on the ballot, or for persons whose names do not appear thereon, but not both; also means for limiting voters on special subjects or in divided precincts, and means enabling the voter to change or cancel his vote, and to prevent tampering before and after the polls close.

These and other ends incident are accomplished by the devices and combination of elements cooperating as hereinafter set forth and stated in the appended claims.

My invention is illustrated by the accompanying drawings, in which similar letters and figures of reference indicate like parts. Referring thereto, Fig. 1 is an end view of my voting machine, the end of the outer case and of the longitudinal members being cut away for better illustration of the interior mechanism. Fig. 2 is an enlarged view of my resetting and grouping mechanism in connection with parts of my irregular and special voting means, hereafter particularly described.

Fig. 3 is a detailed view of my question voting and locking mechanism, hereafter described; and Fig. 4 is a side view of a signal

to limit voters on special questions and objects.

Fig. 5 is a perspective view of a slide-block employed in the grouping mechanism; and Fig. 6 is a like view of a spacer-plate for like purpose. Fig. 7 is a plan view of a portion of the outer case and of the mechanism employed for voting either a straight party ticket or a mixed ticket, and for primary elections.

Fig. 8 is an enlarged plan view of a portion of the mechanism shown in Fig. 7, showing the construction and operation of my detachable push-knobs—or buttons—and their use for voting a straight party ticket and in primary elections. Fig. 9 is a plan view of a portion of the mechanism shown in Fig. 7, showing the cooperation of such push-knobs and the straight ticket and primary mechanism. Fig. 10 is a side view of the means I employ for cancelling the straight ticket mechanism; and Fig. 11 is a plan view of a portion of the outer case and also of the mechanism shown in Fig. 7, showing my primary voting and locking and unlocking mechanism, and Fig. 12 is a side perspective view of my primary signaling mechanism and means for attaching and actuating the same, and for grouping several party rows of candidates. Fig. 13 is an enlarged view of a portion of my straight party ticket and primary slide-bar, detached. Fig. 14 is a perspective view of my resetting mechanism and means for locking and unlocking the voting keys either as a unit or in sections for special or limited voters. Fig. 15 is a detailed view of the tripping means employed to return the primary signals U4 and U5, (Figs. 11 and 12), including a portion of the instrument plate A6, shown in Fig. 17. Fig. 16 is a front view of a portion of the face plate A5, partly cut away to better illustrate the grouping means for the interlocking straps G shown therein.

Fig. 17 is a front view of the means em-

ployed to reciprocate the register-bars H and the resetting-bar J, the latter either in unison or in sections independently, and means for tripping the primary signals aforesaid.

5 The following is a detailed description, (readable on the drawings,) of the construction and operation of each and every essential element of my voting machine, and the cooperation of the several parts, and their 10 functions in attaining the several distinct objects aforesaid of the combined machine.

Parts which function alike in all respects will be illustrated by only one thereof, which is deemed sufficient for the purpose.

15 Referring to the drawings, in Fig. 1, the outer case A, is provided with doors A1, A2, A3, which removably cover the front of the ballot face A5, and shows the plate glass panel Q, over the counters F, and the card 20 ballot receptacle R, and the instrument plate A6, and operating levers thereon, respectively, hereafter described.

25 The framework B, B', B2, and B3, support the interior mechanism; and the longitudinal truss members B4, and B5, support the framework. The several voting keys D, are slideable on the frame, and detachable push-knobs C, are mountable on the keys for use by the voter. A counter actuator E, is 30 pivotally attached to each voting key and extends rearwardly therefrom so as to operatively engage a companion counter when the voting key is pushed in to advanced position, as at D', and the free end of the actuator is impelled upwardly by the adjacent 35 register-bar H, which is reciprocated by the yoke-bar I, as hereafter stated.

Ballot labels are secured on the face-plate A5, by retaining strips in the usual well 40 known way.

The members above stated are substantially shown in my said prior patent, and no claim is specifically made thereto herein.

45 They are shown to better illustrate the novel mechanisms connected therewith, and to enable persons skilled in the art to understand and construct the machine.

It is also to be understood that voting on the machine is accomplished by the voter 50 pushing in the voting keys to indicate his choice, and leaving them pushed in, while hidden from view within a suitable enclosure, as heretofore.

55 Heretofore slideable voting keys, when pushed in to voted position, were temporarily locked therein by an intervening dog, and returned from such position by spiral springs.

60 Such means were too difficult for the voter to change his vote and too uncertain for efficient use.

To overcome these defects and enable the voter to change his vote more freely, and also 65 make impossible any movement of the counters by manipulating the voting keys, and also

provide improved means for locking and unlocking, resetting and relocking the keys, I employ the mechanism particularly shown in Figs. 1 and 2. As seen therein, the voting key D is in normal or unvoted position, and D', is in pushed in or voted position with the push-knob or button C, mounted thereon. Bell-cranks W, alike in all respects, are pivotally mounted on the frame B, immediately above their companion voting keys and in 70 operative engagement therewith, and also with the head of an interlocking strap G, shown in elevated position at G'. The counter actuator on the pushed in key D', appears in advanced position at E', in operative engagement with its companion counter F. 75

A register-bar H, attached to the yoke-bar I, is thereby reciprocally operable vertically across the paths of the several actuators in vertical column, and provided with slots h, (Fig. 14), thru which they reciprocate horizontally, said slots being about $1/8$ inch longer than the width of the actuator, to permit its return without reversing the counter thereby. 80

85 The relation between the counter actuator E, register-bar H, and counter F, is such, that when the voting key D, is pushed in to its limits, as at D', and the register-bar H, is impelled upwardly by the yoke-bar I, to its limits, the units wheel of the counter 90 is rotated forwardly one step, and thereupon, when the voting keys are returned to normal position, as at D, are automatically relocked by the resetting-bar J, in cooperation with the corresponding interlocking strap 95 notches G2, as hereafter stated. Simultaneous locking, unlocking, resetting and relocking all voting keys is accomplished as follows.

100 Cranes i, (only one of which need be shown), are connected to and extend laterally from the yoke-bar I, and the resetting-bar is suspended from said cranes by the hangers j, which permit it to vibrate laterally a limited distance, as indicated by the arrow 105 in Fig. 2.

Both said bars extend from end to end of the machine, and are reciprocated vertically in unison a limited distance by the pair of eccentrics L, L, (Fig. 17), vertically and 110 simultaneously.

To vibrate the resetting-bar J, as aforesaid, a rock-bar K is mounted under the frame base B3, having projecting arms k, (only one of which need be shown), in operative engagement with the resetting-bar whereby the latter may be withdrawn from the strap notches G2, (Fig. 2), by the arm k' when said arm is depressed by the bell crank lever P, as hereafter stated. 120

125 When said arm k' is released, the resetting-bar is automatically drawn into engagement with said notches by the resilient member k2, as shown in Figs. 1, and 2.

The strap notches are about $1/8$ inch longer 130

than the vertical movement of the register-bar and terminate downwardly directly opposite the lower edge of said bar, as at d' , (Fig. 2).

5 It is also essential that the resetting-bar should travel a short distance farther than the upward movement of the straps, so as to freely enter the strap notches; and for this purpose, the arm w' , of the bell-crank W , is 10 about $\frac{1}{4}$ inch longer than the arm w , which engages the upper end of the strap, as at G' , (Fig. 1).

It is apparent that when the resetting-bar engages the strap notches, and all voting 15 keys are in normal (unvoted) position, they are locked by such engagement; and when said bar is withdrawn from said notches, all said keys are thereby simultaneously unlocked; and when said bar is reciprocated 20 downwardly as aforesaid, all voting keys, pushed in, are thereby reset and relocked, and so remain until said bar is again withdrawn from said notches, as aforesaid.

The resetting-bar and actuating mechanism are best shown in Figs. 14 and 17. The rock-bar K , previously referred to, is manually rotatable in one direction to withdraw the resetting bar from the strap notches by the lever $L3$. This actuates the bell-crank 25 lever P , by the intervention of the bar $l3$, between which and said lever $L3$ is formed a toggle joint, (shown in dotted lines). By it said bell-crank lever P , is temporarily locked down upon the adjusting threaded 30 screw $k6$, near the end of the arm k' , until released by the return of the lever $L3$, as follows: A stud l' , projects from the longitudinal bar $L5$, which connects the operating levers $L2$ and $L6$, in such manner as to engage 35 the upper end of the lever $L3$ and impel it rearwardly to the position shown in full lines as returned, when said bar $L5$, is drawn forwardly by said operating levers.

Simultaneously with the return of said 40 lever $L3$, the resetting bar J is automatically drawn into engagement with the interlocking straps G , by the resilient member $k2$, as aforesaid.

To provide means for limiting a class of 45 voters, the resetting bar is divided, and a short section thereof J' is made operable independently of the major portion J , as shown in Fig. 14.

In such case, a short section K' of the 50 rocker-bar K , is also operable independently thereof by the arms $k3$ and $k4$, and by the additional toggle joint lever $L4$, which actuates the secondary bell-crank lever P' , by the connecting bar $l4$, upon the adjusting screw 55 $k5$, near the end of the arm $k4$.

The short section J' is hingedly connected 60 to the extension of the major portion, as shown in Fig. 14, and is operable thereby laterally either in unison therewith, or independently thereof as aforesaid, and the lever

L4 is automatically returned to normal position in like manner as the lever $L3$, above mentioned.

Means including the swivel bar $P2$, in co-operation with the extension p' , of the bell-crank lever P , and the associate bell-crank $P3$, are provided for actuating an external signal, (not shown in the drawings), and are not claimed herein.

The levers $L2$ and $L6$, which, connected by 75 the longitudinal bar $L5$, together actuate the pair of eccentrics L , L , are limited in their sweep to about a quarter circle, to reciprocate the yoke-bar and therewith the register-bars and the resetting bar J the proper distance, 80 in unison, as aforesaid.

Simultaneous operation of the shaft K , and the resetting-bar J , is attained in one direction by their connection together by the arm k , when the arm k' is depressed by 85 action of the bell crank lever P , as shown in Figs. 14 and 17. The said resetting bar is automatically drawn in the opposite direction by the resilient member $k2$, as aforesaid, when the said bell crank lever P is withdrawn 90 by the lever $L3$ to normal position. The latter lever is returned to normal position by the stud l' , by action of the lever $L2$, as shown in Fig. 17, which lever actuates both said eccentrics L , L , and thus determines the 95 relative timing of all the locking and resetting elements aforesaid.

A total vote, or "protective counter" F' is also provided and actuated by one of the 100 register-bars H , as shown in Fig. 1. To provide means for voting either a straight party ticket or a mixed ticket, as the voter may prefer, at general elections, or for choice of party at primary elections, I employ the same operating, registering and resetting mechanism hereinbefore described, in combination with push-knobs and other elements of special character hereinafter described, and further description of features previously mentioned 105 is omitted as unnecessary.

The push-knobs C , are detachably secured 110 on the voting keys D as hereafter described, so that only such as are required for use at the election are visible on the face of the machine.

The stem $d3$, (Fig. 8) of the voting key has a pair of indentations $d4$, at right angles with each other, and the push-knob has a latch $c3$, adapted to engage either of said indentations 120 to removably secure it on the stem in either of two positions.

Each knob has a flat portion on one side thereof, and a hump abutment on its inner end aligned with said flat portion, shown at C' and c' , in Fig. 1, one of said indentations in the stem being adapted to hold said hump c' uppermost thereon, and the other adapted to hold said flat portion uppermost thereon, for a purpose hereafter mentioned.

125 The voting keys extend normally a limited 130

distance beyond the frame B, terminating with said stem.

The slide bar U, is adapted to reciprocate laterally on said extensions d a limited distance, being slidably actuated in one direction by an arm of the rock-bar Z, (Fig. 8), and automatically returned by the return of the straight ticket key to unvoted position, aided by the resilient member u9, as shown in Fig. 7, as hereinafter stated.

A slide-bar U, for each party row of voting keys is mounted upon and adapted to reciprocate across said key extensions, being slidably actuated in one direction by the 15 rock-bar Z, (Fig. 8), and in the opposite direction by the resilient member u9. The slide-bars are in all respects alike, and operate in like manner. Each has a series of lateral projections u', which are spaced apart thereon like the keys of the party row, as shown in Figs. 7, 9 and 11, and extend outwardly just far enough to pass the inner end of an adjacent push-knob when it is in unvoted position and the terminal hump thereon is uppermost, as in Fig. 7.

The rock-bar Z is supported in direct alignment with the vertical column of straight ticket keys, and has a lateral wing z' along one side thereof, which is so located that when the rock-bar is rotated, the tip of said wing will pass freely over the nonactuated straight ticket keys, their extensions being hollowed out for the purpose, as shown in Fig. 8.

Said rock-bar is further provided with a series of lateral arms z2, which are adapted to engage a like series of ribs u, on the slide-bars U, and impel them a limited distance in one direction, when the rock-bar is rotated, 40 which is done by pushing in a straight ticket key. This brings the slide-bar projections u' directly opposite the adjacent hump abutments c' in all party rows, barring all partisan voting keys, leaving only the straight ticket key pushed in.

By the rotation of the rock-bar Z, all said slide-bars are simultaneously actuated, and function in like manner.

When any other than the straight ticket key is pushed in, the push-knob thereon so engages the adjacent projection as to lock the slide-bar and thus prevent advancement of the straight ticket key; and when any one of the straight ticket keys is pushed in, all others are locked by the grouping mechanism aforesaid.

When an advanced straight ticket key is withdrawn, the rock-bar is forcibly reversed by the engagement of its wing with the notch d3, which is provided for the purpose in each straight ticket key extension aforesaid, and thereupon, all said slide-bars are returned to their initial positions, simultaneously, as shown in Fig. 7, by the resilient members aforesaid.

The slide-bar U, in each party row of voting keys, has a series of lateral projections u', spaced apart like the office columns of voting keys, as shown in Figs. 7, 9 and 11. Said projections extend outwardly to a point opposite the inner end of the push-knobs, respectively, and are normally aligned with the flat portion thereof, as shown in Fig. 7.

Said straight ticket rock-bar Z is rotatably supported in vertical alignment with the vertical column of straight ticket keys, and has a lateral wing z', (Fig. 8), which is located so that when said rock-bar is rotated, the tip of said wing will pass freely over the adjacent key extensions, which are hollowed out for the purpose, as shown at d', in Fig. 8. The arrangement is such that when any straight ticket voting key is pushed in to advanced or voted position, as at Z', in Fig. 9, the slide-bar U is drawn laterally by the engagement of said wing and push-knob so as to bring the slide-bar projections u' directly opposite the hump abutments c', thereby locking out all other voting keys in the partly row. Moreover, by pushing in any straight ticket key, all other straight ticket keys are locked by the grouping and interlocking mechanism, hereafter described, which prevents the pushing in of more than one key in the vertical row. To reciprocate the slide-bar U, the lateral arm z2, (Fig. 8), extending from the rock-bar Z, is adapted to engage the transverse bar u, (Fig. 7), and impel the slide-bar in one direction, and when the straight ticket key is returned to normal position, the rock-bar is returned to its initial position by engagement with the stem notch d5 in said key, aided by said resilient member u9, as aforesaid.

With the return of the rock-bar Z the several slide-bars U are therewith returned to their initial positions, simultaneously, as shown in Fig. 7. The tension of the several springs u9 on the slide-bars is such that temporary lockage is required to prevent automatic return, and for such purpose, means for frictionally holding the rock-bar Z in advanced position are afforded by a limiting bar z6, (Fig. 10), in operative engagement with the arm z7 which extends laterally therefrom thru a slot z5. This slot has a slight shoulder z8 at its terminus against which said arm lodges frictionally by pressure of the spiral spring z4, the slot being of proper length to limit the rotation of the rock-bar Z. The rock-bar Z is disengaged from the said lockage by the engagement of its wing with the stem of the pushed in straight ticket key, automatically, when the latter returns to unvoted position, such engagement being sufficient to overcome the said friction of the arm z7 on the shoulder z8 in the slot z5.

Such frictional engagement also enables a

voter to withdraw a pushed in straight ticket key to change his vote, at pleasure.

It will be apparent that after any straight ticket key has been pushed in to advanced position, as at C', Fig. 9, and the push-knobs C are attached to the stem d so that the hump abutment is uppermost thereon, as at c, they will so engage the slide-bar projections u' as to lock the bar and thereby lock all such keys in the party row; and that after any key in the party row is pushed in, as at C', in Fig. 7, said hump abutment will so engage the adjacent slide-bar projection u' as to lock the slide-bar U, and thereby prevent the pushing in of any straight ticket key.

By such means either a straight ticket or a mixed ticket may be voted, at pleasure, but not both.

To provide for voting for non-partisan candidates or groups thereof in connection with voting a straight party ticket, it is only necessary to attach the push-knobs flatwise on the key stems, as at C in Fig. 8, instead of edgewise, as at C' in Fig. 1, such keys may then be voted independently of the straight ticket, altho in the same party row.

Means for rendering the rock-bar Z inactive in case a straight ticket is not required, are provided by the bar z6 in operative engagement with the arm z7, as shown in Figs. 8 and 10, whereby said rock-bar may be entirely disengaged, without any loss of ticket space.

For primary elections it is necessary to provide means for grouping two or more party rows of voting keys to accommodate more numerous candidates than in general elections; also means for unlocking rows of one party, leaving rows of other parties locked; also signals to indicate party tickets, operable either by the voter in secret, or by an election official, as the law may require. For such purpose, the same voting and registering mechanism is employed, as hereinbefore described for general elections. In addition thereto and in combination therewith, the slide-bars U are adapted to be secured together in pairs or groups, as may be desired, by connecting-bars u7, as shown in Fig. 12, operable in unison by the coupling bars u6, respectively.

Party signals U4 and U5 are externally operable independently of each other, and are detachably secured to said bars u6 by the related arms U6 of the signals, respectively, whereby, when either of the signals are drawn outward, as at U4 in Figs. 11 and 12, the related party slide-bars are drawn to the advanced position shown at U3, Fig. 11, thereby unlocking all voting keys of the one party, leaving all other party keys locked; and when both signals remain flatwise on the case, as shown at U5 in Fig. 12, the slide-bars of both parties are, by the connecting bars U6, drawn and held in the position shown at U2, in Fig.

9, thereby locking all party keys by the interposition of the slide-bar projections u' with the push-knob abutments c, as aforesaid.

When the slide-bars of one party are fully drawn out, they are temporarily held in advanced position by means of a latch-bar b, slideable on the frame B, (Fig. 12), said bar being fitted to engage a notch u10 in the slide-bar U, shown in Fig. 13, by the action of a spiral spring b3, (Fig. 12). Operation of more than one signal at a time is prevented by means of the hump u8 at the notch u10 which automatically lifts the latch-bar b out of engagement therewith when another signal is drawn out.

Means for automatically releasing a drawn out signal to its initial position, as at U5, are afforded by a trip a2, located in the instrument plate A6, (Fig. 15), operable by contact with the operating lever L2, as shown in Fig. 17, in connection with the rods b2 and b5, and the intermediate bell crank b4, also shown therein, adapted to raise said latch-bar b, when the yoke-bar I is raised as hereinbefore stated.

The means for actuating and attaching the several party signals may be modified to suit varied conditions.

To provide means for voting for persons whose names are not on the official ballot, a card-ballot receptacle R is removably seated in the case A, as shown endwise in Fig. 1, having a section thereof in alignment with each irregular voting key D2, opening upwardly, a glass door r in front for access thereto, and a number strip r' along its upper edge to identify said sections.

To deposit the card ballots thereon, a chute T extends diagonally downward from a flared opening t in the face below the irregular push-knob, as shown in Fig. 1. To limit the space for admitting the card-ballot singly, and also diminish friction thereof on the chute floor a slight rib t4' is made from its threshold, and a block t2 is seated in the chute having a slight hump t5 immediately above the hump t', and in such near proximity thereto as to limit the space between them to the thickness of the card employed entering freely, and thus prevent repeating.

To deliver the card ballots singly into the receptacle R, a tilt-bar S is pivotally mounted on the post t3 which extends upwardly from the block t2 and terminates at its upper end with a door s, adapted to open and close the mouth t of the chute T, and at its lower end, with an arm s', adapted to open and close the chute outlet and temporarily stop the card ballot until released as hereafter stated. To reciprocate the tilt-bar S, an arm extends upwardly therefrom and is pivotally engaged by a stud s2 to the irregular key D2, so that when said key is pushed in to advanced position, as shown in Fig. 1, the door s is opened thereby and the arm s' is closed to intercept the card

ballot, and when the said irregular key is returned to its initial position by the vote casting mechanism hereinbefore described, the door *s* is closed and simultaneously therewith the arm *s'* is elevated and said card-ballot released. To prevent repetition the irregular key is locked in advance position by the resilient latch *x*, which is adapted to engage the notch *x'* in said key, until disengaged by action of the register-bar *H*, as aforesaid.

Thus either a written or printed ballot may be voted for any office either independently or in connection with the regular voting keys, and registered in like manner.

Propositions submitted may usually be voted upon by the use of any pair of voting keys associated for the purpose. However, it is sometimes necessary to limit voting thereon, permitting one class of voters and preventing others at the same election.

For such purpose, the means, more particularly shown in Fig. 3, are employed in addition to the regular voting means described.

A rotary post *Y*, shown in Figs. 1 and 3, is mounted on a supporting bench *B'* in close proximity to a pair of voting keys *D*3 and *D*4, and extended upwardly thru an aperture *y*3 in the case *A*. Said post is adapted to carry a signal, as shown in Fig. 4, which is employed to rotate the post, and is manually operable by an election official. A short arm *y*7, extending transversely thru the rotary post *Y*, is so located as to lock both said voting keys simultaneously when rotated in one direction, by its engagement at one end thereof with a notch *y*8 in the adjacent key *D*3, and at the other end thereof, with said slide-bar *y*4 in engagement with said key *D*4, and to unlock both said keys simultaneously when said post is rotated in the opposite direction. The slide-bar is reciprocally operable on the bench *B'* a limited distance determined by the length of the slot *y*5. The slide-bar *y*4 is longer than the distance between the voting keys *D*3 and *D*4, so that when one of them is pushed in to advance position, the other will be locked.

The combination is such that when the signal *y*2 is turned in one direction, both said voting keys are simultaneously locked, and when the signal stands at normal position, either, but not both of said pair, may be actuated, as aforesaid.

I am aware it is not new to operate a slide-bar between a pair of voting keys to interlock them, and my claim thereto is limited to the combination of the rotary post and signal, and means employed to reciprocate the slide-bar and to lock and unlock said keys independently, as shown in Fig. 3.

Means constituting a regular and irregular interlock are provided by the particular devices shown in Fig. 2 and in which a pair of register-bars *H*, and *H'* are slidably against each other a limited distance, one

of said bars *H* being connected to and operable reciprocally by the yoke-bar *I*, and the other bar *H'* independently thereof by action of the counter actuator of any voting key in the office column, as follows—including the irregular voting key *D*2 therein—as before described.

As shown in Fig. 2, the counter actuator of the irregular key terminates pointedly, as at *e*, and with a slight shoulder *e'* near its end, and is adapted to engage the slot *h*' in the adjacent slide-bar *H*, and also to enter and engage a like slot in the companion register-bar *H'*, whereby both said bars are held together temporarily and one cannot move vertically independently of the other. The arrangement of all other related slots in said register-bars is such as to stagger them, as shown at *h*2, whereby, when the irregular key is pushed in, as at *D*2, all other voting keys related thereto are simultaneously locked, as at *e*2; and when any one of the related regular voting keys *D* is pushed in to advance position, the companion irregular voting key *D*2 is thereby barred from advancement, and thereupon, as many other related regular voting keys may be voted as the grouping mechanism will permit. Thus a plurality of candidates may be voted for the same office, either of those on the regular ballot, or on the card-ballot, but not both.

I am aware it is not new to stagger slots in a pair of plates which are slidable upon each other, and such I do not broadly claim.

Improved interlocking mechanism for grouping candidates for the same office is provided, as shown in Figs. 2 and 16, wherein groups of interlocking straps *G* are reciprocated vertically thru a longitudinal channel or guideway between limiting slide-blocks and spacer-plates, shown in Figs. 5 and 6, as in my prior patent.

As therein provided, the straps terminate with thickened lower ends formed by bending a limited portion thereof upon itself, as at *g*', Fig. 2, having a beveled shoulder to slidingly engage the said slide-blocks and spacer plates, and such are not now claimed.

Heretofore channels for slide-blocks have been such as to prevent access thereto in order to vary candidate groups.

To avoid such defects, I construct the guideway or channel between longitudinal plates *M*, *M'* and *N*, *N'*, between which the slide-blocks and spacer plates are slidingly interposed and removably secured. Said plates are secured apart from each other on a longitudinal plate or casing *m*, as shown in Figs. 1 and 2, which is suspended from the frame base *B*3 by the angle strip *n*.

To open and close the channel of the guideway a face plate *N*2 is secured on the plate *n*, (Fig. 16), so as to be slidable thereon a limited distance vertically, and hold the slide-blocks and spacer plates slidingly within the

- enclosure, when in closed position. To removably secure the grouping pins *o*' in exact spaced apart positions required for grouping the interlocking straps *G*, a series of notches *o*3 are cut and spaced apart along the lower edge of the face-plate *N*, as shown in Fig. 16, to guide and removably hold said pins, which also extend thru like spaced apart holes in the casing *m*, and thru adjacent slide-blocks, thereby locking and unlocking the latter in the channel. Other means may be provided for securing the grouping pins in position provided they do not prevent opening of the channel.
- 15 Spacer plates, shown in Fig. 6, intervene between the interlocking straps, as heretofore, but are removably secured in the channel and adapted to freely slide therein to serve as abutments, by an extension *o*2, (Fig. 20 6) at the bottom, to slidingly engage the channel plate *N'*, and be manually accessible, Such construction of the guide-way channel, slide-blocks and spacer plates not only avoids the necessity of a longitudinally shift-able channel to provide for large groupings of candidates for office, as heretofore required, but also increases grouping facility by provision for either lengthening or shortening the grouping spaces, by changes in the 30 length of slide-blocks and the introduction of additional spacer plates, or lessening their number for the purpose. Moreover, the provision thus made for easy and direct access to the channel, for the purposes aforesaid, affords better means for regulating the grouping mechanism to suit the varying needs of large and small elections.
- I am also aware it is not new to provide and actuate counters and counter actuators and slidable voting keys, and interlocking straps, and such I do not broadly claim.
- 40 But what I claim as new and desire to secure by Letter Patent is stated in the appended claims, as follows—
- 45 1. In a voting machine having a plurality of slidable voting keys, means for unlocking, resetting and re-locking said keys, comprising in combination, a yoke-bar reciprocably operable, a resetting-bar hingedly connected thereto, an interlocking strap operable by each voting key, each strap having a notch of certain length adjacent the resetting-bar; means for automatically drawing the resetting-bar into engagement with said notches, a rock-shaft having a plurality of lateral arms in operative engagement with said resetting-bar, and a lateral arm to rock said shaft and thereby withdraw the resetting-bar out of said notches, means including
- 50 a bell-crank lever to actuate said last named lateral arm, and means, including a lever with toggle joint to actuate and temporarily lock said bell-crank lever, and means for automatically unlocking and returning the toggle joint lever, and means, including said
- yoke-bar to reciprocate the resetting-bar within said strap notches, substantially as set forth.
2. In a voting machine the combination with a horizontal party row of voting keys, a straight ticket key at the head of said row, a slide-bar movable transversely a limited distance over the keys of said row, said slide-bar having a series of lateral projections extending adjacent each key of the row, respectively, a vertical rock-bar, having a lateral wing thereon, adjacent said straight ticket key, a lateral arm on said rock-bar adapted to engage said slide-bar, a push-knob on said straight ticket key having a terminal hump thereon adapted to engage said wing, a push-knob on every other key in the party row each knob having a terminal hump thereon adapted to abut sidewise against a cooperating slide-bar projection when the key is pushed in to voted position, and endwise when the straight ticket key is pushed in to voted position, substantially as set forth.
3. In a voting machine, in combination with an irregular voting key, means for automatically locking said key when pushed in to voted position, an opening for a card ballot adjacent said key, a chute leading from said opening to a card receptacle, a rib longitudinally disposed on the chute floor, a block spaced apart a limited distance from said rib, a post on said block, a tilt-bar pivotally operable on said post, a door reciprocally operable at one end of said tilt-bar, and an arm thereon reciprocally operable at the other end thereof, an intermediate arm on said tilt-bar in operative engagement with said irregular key, and means, including a register-bar, for automatically unlocking said key for its return to initial position, substantially as set forth.
4. In a voting machine, the combination with a reciprocable register actuating bar having a series of slots therein regularly spaced apart to admit the several counter actuators of regular voting keys, respectively, and a slot aligned therewith to admit the counter actuator of an irregular voting key, said actuators each having a terminal hump adapted to engage said slots, respectively, a slide-bar adjacent said register actuating-bar having a like series of slots therein adapted to register with the slots in said register actuating bar, respectively, except the slot for the irregular voting key actuator, the latter being staggered with respect to the corresponding slot of the register actuating bar, all of said key actuators of a vertical row of keys passing through the slots of the aforesaid bars, thereby providing an interlock between the regular keys and the irregular key.
5. In a voting machine, the combination with a plurality of horizontal rows of slid-able voting keys, a slide-bar slidingly operable on each row of keys, each slide-bar hav-

ing a series of lateral projections for co-operation with each key of the row, respectively, means coupling two or more slide-bars to slide in unison, a push-knob on each key in use having a terminal hump abutment adapted to engage a slide-bar projection when aligned therewith, a primary election signal manually operable on the machine case, means for detachably securing said signal to said 10 coupled slide-bars to draw the latter endwise a limited distance until the projections thereon are opposite said hump abutments, respectively, means, including said signal, for drawing said slide-bar projections beyond 15 said hump abutments respectively, means for temporarily locking said slide-bar in advanced position, and means for automatically unlocking a slide-bar of one party when the slide-bar of another is drawn to advance 20 position, and means for returning advanced slide-bars to initial position automatically, substantially as set forth.

6. In a voting machine, a resetting and re-locking bar, comprising in combination, a 25 major and a minor section reciprocally operable in unison, the minor section being hingedly secured to the major section and reciprocating therewith, and adapted to swing independently thereon a limited distance, and 30 means, including a pair of rock-bars operable independently of each other, to swing said sections, respectively, sidewise, independently of each other, and resilient means for automatically returning said sections to their respective initial positions, substantially as set forth.

7. In a voting machine having a horizontal row of slidable voting keys, a slide-bar slideable transversely over said row, and equipped 40 with projections aligned with said keys, respectively, each key terminating outwardly with a stem, a pair of notches at right angles with each other in said stem, a detachable push-nob fitted to and mountable on said 45 stem, said knob being flattened along the inner portion of one side thereof, and having a hump abutment at its inner end aligned with said flat portion, means including a latch operable on said knob, adapted to engage 50 either of said notches interchangeably so as to hold said hump abutment either vertically into operative engagement with the corresponding projection on said slide-bar, or flatwise with respect thereto.

55 8. In a voting machine, in combination with a bench, a pair of slidable voting keys spaced apart thereon, a plate reciprocally operable between said pair, said plate being longer than the distance between said pair, 60 and slideable by the endwise pressure of either to a position in front of the other to lock it from advance movement, and means, including said plate, for locking both keys simultaneously, comprising a rotatable post on said 65 bench adjacent one of said keys, an abutment

on said plate opposite said post, a notch in the key opposite said post, and a bar thru said post adapted to intervene between said abutment and said notch when the post is rotated in one direction, and to be disengaged 70 from both when rotated in the opposite direction, as set forth.

In witness whereof I hereunto set my hand this 21st day of March A. D. 1927.
